UNITED STATES PATENT OFFICE.

JAMES SHARKEY, OF BROOKLYN, NEW YORK.

DESIGN FOR A MONUMENT.

Specification forming part of Design No. **6,693**, dated May 27, 1873; application filed May 5, 1873.

To all whom it may concern:

Be it known that I, JAMES SHARKEY, of Brooklyn, in the county of Kings and State of New York, have invented a new and original Design for Monument, of which the following is a specification:

The nature of my design is fully represented in the accompanying photographic illustration, to which reference is made.

A is the base; B is the pedestal; C is the

cap of the pedestal; D is the shaft; and E is the cap of the shaft; the latter terminating in a cone or pyramid, as represented.

I claim as my invention—

The design for a monument, substantially as shown and set forth.

JAMES SHARKEY.
